UNITED STATES PATENT OFFICE

ERNEST WILLIAM SIMMONS, OF MARFRANCE, WEST VIRGINIA, ASSIGNOR, BY DIRECT AND MESNE ASSIGNMENTS, OF ONE-THIRD TO JAMES H. GIBSON, OF MARFRANCE, WEST VIRGINIA, AND ONE-THIRD TO ROY H. NELSON, OF QUINWOOD, WEST VIRGINIA

AUTOMATIC CAR COUPLER

Application filed February 4, 1932. Serial No. 590,930.

This invention relates to an automatic car coupler designed primarily for use in connection with mine cars, but it is to be understood that a car coupler in accordance with 5 this invention may be employed in any connection for which it may be found applicable, and the invention has for its object to provide, in a manner as hereinafter set forth, a coupler for cars so constructed and arranged 10 as to insure expeditious and automatic coupling of a pair of cars together, and further including means for quickly releasing the coupled cars from each other when occasion requires, as well as for reducing to a minimum 15 the accidental uncoupling of the cars when rounding curves.

Further objects of the invention are to provide, in a manner as hereinafter set forth, a resilient, flexible, spring controlled automatic car coupler which is comparatively simple in its construction and arrangement, strong, durable, compact, thoroughly efficient in its use, conveniently released when occasion requires, readily assembled, quickly installed with respect to a car, and comparatively inexpensive to manufacture.

To the above ends essentially and others which may hereinafter appear, the invention consists of such parts and such combination 30 of parts as fall within the scope of the invention as claimed.

In the drawing wherein like reference characters denote corresponding parts throughout the several views:—

35 Figure 1 is a sectional plan of a car coupler in accordance with this invention.

Figure 2 is a section on line 2—2 of Figure 1.

40 Figure 3 is a section on line 3—3 of Figure 1.

The car coupler includes a retainer section carried by one end and a bumper section carried by the other end of a car. The retainer section of one car acts to retain a 45 bumper section of another car in coupling relation. The retainer and bumper sections are indicated generally at 1, 2 respectively.

The section 1 includes a body part 3 formed of a pair of superposed oppositely disposed like sections secured together in a manner to

be presently referred to. The front of body part 3 is of convex curvature. A pair of side members 4, 5 are secured to the sides of body part 3 and extend backwardly therefrom and abut against a vertically disposed back plate 55 6. A top plate 7 is positioned upon and a bottom plate 8 is arranged against the lower face of body part 3. The plates 7, 8 bear against the lengthwise edges of the back plate 6. The plates 7, 8 extend backwardly from body part 3 and in connection with the latter and plates 4, 5 provide a compartment 10 at the back of body part 9. The plates 7, 8 register with the front of body part 3. Fastening means 11 are employed for connecting plates 7, 8 together, the sections of body part together and the plates 7, 8 and body part together.

The body part 3 at its transverse median is formed with a horizontally disposed, flared, 70 oval shaped slot 12 and a flared opening 13. The slot 12 and opening 13 are oppositely disposed with respect to each other. The slot 12 communicates at its inner end with the front end of opening 13. The slot opens at the front of body part 3. The opening 13 communicates with compartment. The horizontal length of slot 12 is greater than the diameter of opening 13.

75 Slidably mounted in a pair of endwise opposed grooves 14 formed in body part 3 is a pair of oppositely disposed, spring controlled coupling heads 15 of like form. The grooves 14 are intersected by the slot 12. 80 Each head 15 has its inner end provided with a projection 16 having a beveled face 17 and a flat back face. Controlling springs for the heads are designated 18. Each projection has a curved edge 19. The body part 3 is 85 formed with spaced rectangular slots 20 which open into the grooves 14. Secured to the heads 15 and extending therefrom through the slots 20, as well as projecting into chamber 10, are pins 21 which are attached to a link 90 and lever mechanism 22 for shifting the heads 15 apart against the action of the controlling springs 18. The mechanism 22 includes an operating lever 23, which is pivotally attached to body part 3, as at 24, and extends upwardly 95 100

through a slot 25 provided in the top of compartment 10.

The coupling section 2 includes a body part 26 formed of a pair of oppositely disposed sections of like form. The body part 26 has its front of convex curvature and at its transverse median it is formed with a horizontally disposed flaring slot 27 opening at said front. The body part 26 at its transverse median 10 is also formed with a hemispherical shaped pocket 28 which opens at the back of body part 26 and communicates at its base with the inner end of slot 27. The horizontal width of the latter is less than the diameter of 15 pocket 28 at the mouth or rear end of the latter. The slot and pocket are oppositely disposed with respect to each other. The depth of the slot is less than that of the pocket.

Secured against the back of body part 26, 20 centrally with respect to the latter, is a cylinder 29 of a diameter greater than that of the mouth of pocket 28. The cylinder is disposed concentrically with respect to the mouth of pocket 28 whereby that portion of 25 the back of body part 26 extending from the inner face of the cylinder to pocket 28 provides a shoulder 30. Positioned against shoulder 30 and housed within cylinder 29 is a spring controlled plate 31 of greater diameter than the mouth of the pocket 28. The plate 30 31 constitutes a closure for the pocket and has its movement in one direction arrested by the shoulder 30. Housed within cylinder 29 and seating against plate 31 is a combined controlling and cushioning spring 32 for such plate. The spring 32 is of a diameter to seat against the plate 31 in close proximity to the edge of the latter.

Mounted against the top and bottom of 40 body part 26 are plates 33, 34 respectively which are flush with the front of body part 26 and extend backwardly therefrom. Side and back plates 35, 36 respectively are positioned between plates 33, 34. The plates 33, 34 are 45 clamped together and to the body part 26 by the fastener means 37 which also clamp plates 35, 36 in position, but these latter may be welded to plates 33, 34. The plates in connection with body part 26 provide a chamber 50 38 in which is arranged the cylinder 29, and the rear end of the latter is closed by plate 36.

The bumper section 2 includes a freely movable coupler pin 39 comprising a shank 40 of the desired length which at its inner end 55 is integral with and perpendicular to the curved face 41 of a solid hemispherical shaped head 42 having its flat face indicated at 43. The outer end of the shank 40 is integral with and perpendicular to the rear or holding face 44 of a circular holder portion 45 of materially greater diameter than that of the shank. The holder portion 44 merges into a tapered part 46 at the outer end of the pin 39.

65 The head 42 is arranged in pocket 28 and

has its curved face 41 conform to the shape of the pocket. The face 41 of head 43 rides against the wall of pocket 28. The flat face of head 42, which is of less diameter than plate 31, bears against the latter. The plate 31 and spring 32 normally function to maintain the pin 39 extended with respect to body part 26, that is to say the spring 32 bears upon the outer edge of the flat face 41 of head 42, throughout its circumference, in order to hold the pin 39 extended horizontally. The spring 32 also functions as a cushion for the pin. The shank 40 extends through slot 27 and is of a material greater length than the depth of the slot.

The pin 39 is for extension through slot 12, opening 13 and into chamber 10. As pin 39 passes through slot 12 the tapered part 46 forces the coupling heads 15 apart against the action of their controlling springs 18. After the holding portion 45 has cleared the heads 15, these latter will be forced to engage the shank 40 outwardly of and have the flat faces of their projections 16 oppose the face 44 of holder portion 45 whereby the sections 1 and 2 will be coupled together.

The horizontal width of slot 12 is materially greater than that of slot 27. The depth of slot 12 is greater than that of slot 27, as well as that of opening 13. The length of portion 45 is materially less than that of shank 40.

What I claim is:—

1. In a car coupler, a bumper section provided with a body part formed with a horizontally disposed, flared slot and a hemispherical shaped pocket, said slot opening at the front of said body part and communicating with said pocket at the base of the latter, said pocket opening at the rear of said body part, a coupler pin including a hemispherical shaped head and a shank extending through said slot and merging at its inner end in the curved face of the hemispherical head and at its outer end in a holder portion having a tapered part extended therefrom, said head seated in said pocket and having a flat inner face, said body part being formed with a shoulder bordering the mouth of said pocket, a plate of greater area than and arranged concentrically to said flat face, said plate abutting said shoulder and flat face and closing said pocket, a controlling spring bearing against the edge of one face of said plate throughout its circumference whereby force is transmitted from the plate to the head to hold the pin extended horizontally, and means for holding the plate and spring in position.

2. In a car coupler, a bumper section provided with a body part formed with a horizontally disposed, flared slot and a hemispherical shaped pocket, said slot opening at the front of said body part and communicating with said pocket at the base of the latter, said pocket opening at the rear of

said body part, a coupler pin including a hemispherical shaped head and a shank extending through said slot and merging at its inner end in the curved face of said head
5 and at its outer end in a holder portion having a tapered part extended therefrom, said head seated in said pocket and having a flat inner face, said body part being formed with a shoulder bordering the mouth of said
10 pocket, a plate of greater area than and arranged concentrically to said flat face, said plate abutting said shoulder and flat face and closing said pocket, a coiled spring having one end bearing against the edge of said
15 plate throughout its circumference whereby force is transmitted from the plate to the head to hold the pin extended horizontally, a cylinder housing the plate and spring, and a supporting means for the cylinder secured
20 with said body part.

3. A car coupler, a bumper section comprising a body part formed with a horizontally disposed flared slot and a hemispherical shaped pocket communicating with the slot,
25 said slot and pocket being oppositely disposed, a coupler pin extending through said slot and having a solid, hemispherical shaped head seated in said pocket, said head having a flat face, said slot opening at the front
30 and said pocket having its mouth at the rear of said body part, said body part formed with a shoulder bordering the mouth of said pocket, a plate arranged rearwardly of said body part and bearing against said head and
35 shoulder, a spring seating against said plate to bear against the edge of one face of the plate throughout its circumference whereby force is transmitted from the plate to the head to hold the pin extended horizontally.

40 4. A car coupler, a bumper section comprising a body part formed with a horizontally disposed flared slot and a hemispherical shaped pocket communicating with the slot, said slot and pocket being oppositely disposed,
45 a coupler pin extending through said slot and having a solid, hemispherical shaped head seated in said pocket, said head having a flat face, said slot opening at the front and said pocket having its mouth at the rear of said
50 body part, said body part formed with a shoulder bordering the mouth of said pocket, a plate arranged rearwardly of said body part and bearing against said head and shoulder, a spring seating against said plate to bear
55 against the edge of one face of the plate throughout its circumference whereby force is transmitted from the plate to the head to hold the pin extended horizontally, and a combined housing and supporting means for
60 the plate and spring for holding them in position, said means being secured to said body part and extended rearwardly therefrom.

In testimony whereof, I affix my signature hereto.

35 ERNEST WILLIAM SIMMONS.
